DESIGN FOR A COLLAR

Arnold Livingston, New York, N. Y.

Application March 20, 1939, Serial No. 83,688

Term of patent 3½ years

To all whom it may concern:

Be it known that I, Arnold Livingston, a citizen of the United States, residing in New York city, in the county of New York and State of New York, have invented a new, original, and ornamental Design for a Collar, of which the following is a specification, reference being had to the accompanying drawing, forming part thereof.

Figure 1 is a front view of a collar showing my design.

Figure 2 is a front view thereof on its reverse side, and

Figure 3 is a plan view in extended position thereof.

The characteristic feature of my design resides in the combination on the reversible double collar disclosed of a collar having rounded corners superimposed on a pointed collar as shown.

I claim:

The ornamental design for a collar, substantially as shown and described.

ARNOLD LIVINGSTON.
